UNITED STATES PATENT OFFICE.

JOHN GODFREY PARRY THOMAS, OF CHISWICK, ENGLAND.

ELECTRICAL CONTROLLER.

1,005,084.

Specification of Letters Patent.

Patented Oct. 3, 1911.

Application filed February 3, 1910. Serial No. 541,700.

To all whom it may concern:

Be it known that I, JOHN GODFREY PARRY THOMAS, a subject of the King of Great Britain, residing at 21 Ennismore avenue, Chiswick, in the county of Middlesex, England, electrical engineer, have invented new and useful Improvements in and Relating to Electrical Controllers, of which the following is a specification.

10 This invention relates to controllers for dynamo electric machines, in which the requisite changes of connection are effected by means of a set of pairs of contacts arranged adjacent to a drum, in such manner 15 that suitable cams on the drum can in the required order press one contact of a pair against its fellow, and keep them in contact for the requisite times.

The present invention has for its object 20 the better lubrication of the drum and the cam surfaces.

To this end the invention comprises a casing adapted to contain oil in which the drum rotates.

25 A further purpose of the invention is the production of a compact controller.

More particularly the invention is designed to combine several sets of contacts with a single drum. Also the invention aims 30 at improving the efficiency of the controller by enabling the making of better contacts.

More specifically the invention comprises a contact so adapted that it can rock or rotate in order to bed itself down upon its 35 fellow.

Yet another object of the invention is to provide means for dismantling a controller without interfering with the numerous connections thereto.

40 Examples of construction are illustrated in the accompanying drawings in which—

Figure 1 is a cross sectional elevation of a controller, and Fig. 2 a detail thereof being a section on the line A—B of Fig. 1. Fig. 3 45 is a cross sectional elevation of a modified form.

In the drawings, 1 is the controller drum to which are secured projecting cams 2 of suitable length and suitably spaced relatively to one another. Beside the drum and parallel to its axis is a column 3 upon which are mounted a series of arms 4, the tails 5 of which are connected by springs 6 to a bar 7. The arms 4 carry projecting pins 55 35 adapted to bear on the surface of the

drum against which they are pressed by the tension of the spring 6. These arms also carry one set of electrical contacts.

The contact is preferably made up of a metal strip 8 separated from the arm 4 by a strip of fiber 9 between which strip and a second piece of insulating material 10 it is clamped by means of a screw 11 passing through a lug 12 formed on the arm. To the end of the thin metal strip 8 is secured the contact proper 13 and this is joined by a flexible strip 14 to a contact piece 15 secured upon an insulating bar 16. This bar carries terminals for all the contacts 13, the terminals being joined to the appropriate resistances or the like with which the controller has to deal. The bar 16 is itself secured upon a metal bar 17 supported upon the end plates of the casing 18 in which the whole controller is inclosed.

To allow of the contact 13 bedding down upon the contact brush 20 it is convenient to bevel the fiber strip 9 on its upper surface, as seen in Fig. 2, so that the contact can rock a little.

The fixed contacts are supported upon another metal bar 19 which similarly rests in slots in the end plates of the casing. The contacts proper comprise laminated brushes 20 preferably formed with a prolonged outer lamination 21 arranged to receive the break. This strip 21 may, if desired, be separated from the rest by a layer of carbon so as to introduce a resistance into the circuit before breaking, or an actual carbon break may be provided. The brush is separated from the bar 19 by a strip of insulation 22, being held by bolts and nuts 23 bearing upon another insulating strip 24. The metal piece 25 lies in contact with the brush and carries the terminal to which is connected the flexible lead 26 leading to the motor or other external part through the opening 27 in the end wall of the casing 18.

Where the number of connections to be made is considerable, so that a large number of contacts are required, it is convenient to provide two columns 3, as shown in the drawing, one on either side of the main drum. The contacts 13 are necessarily of considerable width and therefore the number that can be arranged in a given length is limited. The cams 2, however, need only be of very small width and consequently by using two sets of contacts, staggered 105 110

relatively the one to the other, with a single drum a considerable amount of space is saved. Obviously three or even more columns could be employed if desired.

5 Preferably the drum 1 is arranged horizontally as shown, and the casing is formed with a semicylindrical recess 28 fitting the drum fairly closely, with, of course, sufficient space for the cams. This recess may 10 be filled with oil which will be carried up by the drum in rotating and will serve the purpose of lubricating its bearings and also lessen the friction between the pins 35 and the cams 2. If desired, rollers may be provided in place of the pins 35. The casing may be so designed as to immerse the contacts also in oil; this renders possible a diminution in the size of the contacts and does not introduce any resistance between 20 the contact surfaces.

In the construction shown in Fig. 3 the contacts are arranged rather below the drum than above. The lower part 38 of the casing having a cover 39 is adapted to contain 25 oil within which the drum 1 rotates. The flexible connections 14 extending from the moving contacts are combined with steel springs 40, which replace the springs 6 of Fig. 1 and serve to press the pins 135 30 against the drum 1 or its cams 2. The actual contact piece 41 is mounted upon an insulated steel spindle 42 supported in the arm 4. A beveled backing 43 is provided between the contact and the end of the arm 4 so that the contact may easily rock upon its shaft. This provides for the requisite bedding down upon the fixed contact 20.

The connections to the external circuit are by suitable metal bars 44, 45, joined to bolts 56, which pass out through insulating sleeves 46 at the top of the casing and terminate in cones 57. Outside the casing is provided a cap 47 secured in place by a cross bar 48, lugs 49 and bolts and nuts 50. Within the cap bears ribs 51 which support by means of insulating sleeves 52 the bolts and nuts 53 to which are connected the leads passing to the rheostats and motors. The bolts 53 are free to slide within the sleeves 52 and their enlarged ends 58 have conical recesses fitting the cones 57. The bolts are normally pressed down to make contact with the cones by means of springs or spring washers 59. This construction enables the controller 55 proper to be dismounted without interference with the various connections to the external circuits. The cap 47 can be removed carrying with it all the external connections to the bolts and nuts 53, the contacts being 60 broken of course at the cones 57, 58. When the cap is replaced all the contacts are immediately made without chance of error, the cones being pressed together by the springs or spring washers 59. These springs moreover, serve to allow for any differences there

may be between adjacent connector bolts so that good contact is secured in each place.

It is possible to have the controller contacts normally pressed together by the spring and separated by the cam action, or by the use of a cam groove or the like both movements may be positively controlled. If desired a controller of this form may suitably be combined with a rheostat by providing a series of contact studs at one end of the casing in which the drum is mounted and attaching a bridging arm to the drum spindle. This arrangement is particularly of service in connection with the control of machines employed for the transmission of power on motor vehicles and so forth.

What I claim is:—

1. The combination of a drum, cams upon said drum, pairs of pivoted and fixed contact supports adjacent to said drum, contacts upon said supports, means upon one support of each pair enabling the contact thereon to rock in a plane parallel to the pivot, and means upon the movable support enabling it to be operated by the drum.

2. The combination of pairs of electrical contacts, rigid supports therefor, means for causing one contact of each pair to move toward or away from the other, and means interposed between one contact of each pair and its support enabling said contact to rock but not yield.

3. The combination of a drum, cams thereon, pivoted contact supports adapted to be moved by said cams, contacts rotatably mounted on said supports so as to oscillate in a plane at right angles to the plane of movement of said supports, and fixed contacts mounted adjacent to said moving contacts.

4. The combination of a drum, cams upon said drum, contact supports pivoted adjacent to said drum, spindles on said supports at right angles to the pivots, contacts pivoted on said spindles, and fixed contacts adjacent to said pivoted contacts.

5. The combination of a casing, a drum rotatable therein, cams thereon, pairs of contacts adjacent to said drum, terminals mounted independently of said contacts and connections between said terminals and the contacts.

6. In an electric controller, the combination of a frame, pairs of relatively movable contacts, means causing one contact of each pair to move toward or away from the other, conical terminals connected each to one contact of one pair, a member detachable from said frame, spring mounted terminals on said member having conical recesses, and means connecting said member to the frame so as to press respective terminals together.

7. In an electrical controller the combination of a frame, pairs of relatively movable contacts therein, a plurality of insu-

lated terminals in said frame each connected to one contact of a pair, a detachable member joined to said frame by bolts, terminals mounted in said member opposite the terminals in the frame, and spring means interposed between the second member and the terminals mounted in it.

8. In an electric connecting device the combination of a drum bearing cams, pairs of contacts adjacent to said drum, terminals connected to said contacts, independent terminals mounted upon a removable member and means pressing the two sets of terminals together.

15 9. In an electric controller, the combination of a drum bearing cams, pairs of contacts adjacent to said drum, one contact of each pair being movable, a projection on said movable contact adapted to coöperate with a cam on the drum, a casing surrounding said drum and contacts, connectors passing from said contacts through said casing,

and a removable cap bearing contact pieces spring pressed toward said connectors.

10. In an electrical connecting device the combination of a casing, a drum bearing cams rotatably mounted in said casing, pairs of contacts arranged adjacent to said drum and adapted to be pressed together by said cams, a cover upon said casing, insulated terminals mounted in said cover and connected to said contacts, a removable cap, bolts pressing said cap upon said cover, and spring mounted terminals in said cap adapted to abut upon the terminals in the cover.

In testimony whereof I have signed my name to this specification in the presence of two subscribing witnesses.
